UNITED STATES PATENT OFFICE.

CHARLES EDWARD HAVILAND, OF LIMOGES, FRANCE.

DESIGN FOR A PLATE.

SPECIFICATION forming part of Design No. 21,683, dated July 5, 1892.

Application filed June 7, 1892. Serial No. 435,894. Term of patent 14 years.

To all whom it may concern:

Be it known that I, CHARLES EDWARD HAVILAND, a citizen of the United States, residing at the city of Limoges, in the Republic of France, have invented and produced a new and original Design for a Plate and other Articles, of which the following is a specification, reference being had to the accompanying drawings forming part thereof, and in

10 which—

Figure 1 is a top view of a plate bearing my design; Fig. 2, a detached section of same on the dotted line 2 2 of Fig. 1, and Fig. 3 a detached section of same on the dotted line 3 3

15 of Fig. 1.

The leading feature of my design consists of the ornamental looped configuration A, ex-

tending around the plate and shown as though caught or held by rosette-pins B, as illustrated in Fig. 1, thereby producing a conventionalized lambrequin effect. The edge of the plate is composed of the scallops C, and between this edge and the looped configuration A is the line of beads D and the field covered with the short bars E.

25

What I claim is—

The design for a plate or other article, substantially as shown and described.

Signed at the city of Limoges, in the Republic of France, this 25th day of May, 1892.

30 CHARLES EDWARD HAVILAND.
